DRILL

Joseph Welny, Denver, Colo.

Application July 16, 1940, Serial No. 345,790

3 Claims. (Cl. 77-32)

This invention aims to provide a novel drill feed and a novel means whereby the drill may be retracted quickly from working position.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in elevation, a machine wherein the invention is embodied;

Fig. 2 is a cross section on the line 2-2 of Fig. 1;

Fig. 3 is a cross section on the line 3-3 of Fig. 1;

Fig. 4 is a vertical section showing a part of the drill feed which forms the subject matter of this application.

Fig. 5 is a horizontal section wherein most parts appear in plan, the view depicting the parts as they will appear whilst the drilling operation is going on;

Fig. 6 is a view similar to Fig. 5, but illustrating the parts as they will appear whilst a feed of the drill is taking place;

Fig. 7 is a view similar to Figs. 5 and 6, but showing the parts as they will appear during the operation which consists in retracting the drill.

The supporting frame shown in Fig. 1 may include a base 4, held on a work bench 1 by clamps 2. The work is shown at 6, and is adapted to be perforated by a vertical drill 7, and the base 4 has an elongated opening 8 which permits the drill 7 to get at the work 6.

Posts 11 are located on the base 4. Headed studs 22 and 21 are fixed, respectively, in the upper ends of the posts 11 and hold blocks 23 on the upper ends of the posts.

The numeral 27 marks an elongated rectangular track, the ends of which are attached to the blocks 23.

A support or rider 31, of rectangular cross section, is guided between the side portions of the track 27, for movement lengthwise of the track. The rider 31 has a top flange 32, engaging the upper surface of the track 27. The top flange 32 of

the rider 31 is supplied with a depending index 33, which, cooperating with a longitudinal scale 34 on the track 27, makes manifest to the operator, the position to which the rider has been adjusted, lengthwise of the track. The rider 31 is equipped with a lower flange 35, engaging the lower edge of the track 27. The lower flange 35 carries perforated ears 36, having nothing to do with the set up shown in Fig. 1. The top flange 32 of the rider 31 is supplied with an arm 37 extended lengthwise of the track 27 and provided with an upstanding finger 38, having an inner cam surface 39. The function of the cam surface 39 will be made manifest hereinafter.

A sleeve 40 is mounted to rotate in the rider or support 31, although rotation of the sleeve at times is stopped, by a mechanism to be described hereinafter. Downward movement of the sleeve 39 is prevented by a toothed wheel 41, secured to the upper end of it and disposed above the top flange 32 of the rider. The wheel 41 may be regarded as part of the sleeve. Upward movement of the sleeve 40 is prevented by a hand wheel 42, secured to the lower end of the sleeve, anti-friction balls 43 being interposed between the hand wheel and the lower flange 35 of the rider 31.

A screw shaft 44 is threaded into the sleeve 40, and carries a handle 45 at its upper end. A chuck 46 is secured to the lower end of the shaft 44 and carries the drill 7. When the shaft 44 is rotated by the handle 45, the drill is rotated, and the drill cooperates with the work 6. When it is desired that the shaft 44 and the drill 7 shall feed downwardly, this can be done by holding the wheel 42 in the hand of an operator, the sleeve 40 thus being prevented from turning. The hand feed thus employed is useful, but is not the most important mechanism by which the shaft 44 and the drill 7 can be fed downwardly to the work 6. Another mechanism, next to be described, is employed for feeding the shaft 44 and the drill 7 downwardly, automatically.

A disk 47 is secured to the wheel 41 and forms an outstanding flange on the wheel. A cross arm 48 is mounted to swing on the screw shaft 44, the edge of the disk 47 being engaged in the cross arm, as shown at 49, on opposite sides of the shaft 44, to hold the cross arm in place. A pawl 50 is fulcrumed intermediate its ends 51 on one end of the arm 48. One end of the pawl 50 has a head 52 shaped to engage the teeth of the wheel 41.

A dog 53 is connected by a pivot element 54 to the end of the pawl 50 that is remote from

the head 52. The dog 53 has teeth 60 for engagement with the teeth of the wheel 41. A latch 55 is fulcrumed intermediate its ends, at 56, on the arm 48. The outer end of the latch 55 is connected to the dog 53 by a pull spring 57. The inner end of the latch 55 is adapted to engage a shoulder 58, formed by one wall of a longitudinal groove 59 in the shaft 44.

If the parts are disposed as shown in Fig. 5, when the shaft 44 is rotated clockwise, in the direction of the arrow, the latch 55, cooperating with the shoulder 58 in the shaft 44, causes the cross arm 48 to move in the direction of the arrow. The head 52 of the pawl 50 is engaged with the teeth of the wheel 41 and the wheel is caused to rotate clockwise. During this operation, the dog 53 acts as a brace, preventing the tilting of the pawl 50 on the pivot element 51, the head 52 of the pawl 50 being kept engaged with the teeth of the wheel 41. When the wheel 41 is rotated, as aforesaid, it turns along with the shaft 44, and the shaft is not fed downwardly, as it is rotated.

As the arm 48 moves clockwise, the knuckle joint at 54, between the dog 53 and the pawl 50, engages the cam surface 39 on the finger 38 of the arm 37 on the rider 31, the rider being engaged in the track 27 against rotation.

As the knuckle joint at 54 rides along the cam surface 39, the angle between the dog 53 and the pawl 50 is increased, and the pivot element 54 is caused to move inwardly. The pawl 50 is swung on its fulcrum 51, and the head 52 of the pawl is swung clear of the wheel 41, as in Fig. 6.

The wheel 41 thus is uncoupled from the arm 48, so far as getting a clockwise thrust from the pawl 50 is concerned. The sleeve 40 does not receive positive clockwise rotation from the pawl 50, and if the sleeve can be held against rotation due to the friction drag of the rotating screw shaft 44, the screw shaft will be fed downwardly, and the drill 7 of Fig. 1 will be advanced with respect to the work, so long as the knuckle joint at 54 is in engagement with the cam surface 39.

Reference has been made immediately hereinbefore to the fact that the sleeve 40 should be held against clockwise rotation due to the friction drag of the rotating screw shaft 44. In that connection, note that the teeth 60 of the dog 53 (Fig. 6) remain engaged with the teeth of the wheel 41 whilst the head 52 of the pawl 50 is disengaged from the teeth of that wheel.

As the knuckle joint at 54 moves along the cam surface 39, the knuckle joint is carried inwardly toward the axis of the shaft 44. This gives to the dog 53 a counterclockwise component which substantially offsets the clockwise component due to the fact that the knuckle joint at 54 is moving clockwise along the cam surface 39. The result is that the wheel 41 and the sleeve 40 are held definitely against clockwise rotation, and as the screw shaft 44 is rotated, it feeds downwardly through the sleeve 40. This downward feeding of the screw shaft 44 is of short duration. It continues only so long as the knuckle joint at 54 is riding along the cam surface 39. After the knuckle joint at 54 clears the cam surface 39,

the toothed part 60 of the dog 53, and the head 52 of the pawl 50 are restored to the engaged relation with the toothed wheel 41, shown in Fig. 5.

5 When it is desired to retract the screw shaft 44 and the drill 7, the dog 53 is turned outwardly, to the position of Fig. 7, the pull of the spring 57 on the latch 55 being released. Counterclockwise rotation, in the direction of the arrow, is imparted to the screw shaft 44, the knuckle joint at 54 ultimately coming into contact with the end 61 of the fixed finger 38. Movement of the arm 48, in a counterclockwise direction, is stopped, and counterclockwise rotation of the sleeve 40 is stopped, because the head 52 of the pawl 50 is engaged with the toothed wheel 41. The screw shaft 44 thereupon will feed upwardly, raising the drill 7 with respect to the work.

The pawl 50 is provided with an opening 51' for reception of the fulcrum pin 51. When a more rapid feed of the drill bit is desirable the pawl 50 is mounted with its fulcrum at 51', thereby lengthening the lever on which the dog 53 is mounted and increasing the travel of the dog.

Having thus described the invention, what is claimed is:

1. In a drill feed, a support, a sleeve mounted to rotate in the support, a drill shaft threaded into the sleeve, means for rotating the drill shaft directly, an arm mounted to swing on the drill shaft, a releasable connection between the arm and the drill shaft, a pawl fulcrumed intermediate its ends on the arm, one end of the pawl being engageable with the sleeve to cause the sleeve to rotate directly, with the drill shaft, a dog pivoted to the opposite end of the pawl, the pivotally connected ends of the pawl and the dog forming a knuckle joint, means for maintaining the dog yieldably engaged with the sleeve, and a fixed cam wherewith the knuckle joint engages, as the arm travels directly, to move the knuckle joint toward the shaft, thereby to disengage the pawl from the sleeve and to impart to the dog a reverse component, neutralizing the direct component resulting from the travel of the knuckle joint along the cam, the sleeve thereby being held substantially fixed, whereby the drill shaft will feed therethrough, when the drill shaft is rotated directly.

2. A drill feed constructed as set forth in claim 1, and wherein the releasable connection is a shaft-engaging latch pivotally mounted on the arm, the means for maintaining the dog yieldably engaged with the sleeve being a retractile spring connected to the dog and to the latch and constituting assisting means for maintaining the latch engaged with the shaft.

3. A drill feed constructed as set forth in claim 1, and wherein the dog is movable to disengage it from the sleeve, to present the knuckle joint prominently, one end of the cam constituting an abutment wherewith the knuckle joint engages, to stop reverse rotation of the arm and the sleeve, when reverse rotation is imparted to the shaft and whilst the pawl is engaged with the sleeve.

JOSEPH WOLNY.
